UNITED STATES PATENT OFFICE.

JESSE R. MEEKINS, OF MARSHALLTOWN, IOWA.

CURRENT MOTOR.

Application filed May 10, 1927. Serial No. 190,296.

This invention relates to current motors and more particularly to a device of this character adapted to operate while submerged or partially submerged in a stream.

5 An important object of the invention is to provide an improved blade construction for use in conjunction with apparatus of this character such that the blades may readily fold or feather during that portion of the 10 travel when they are opposed to the direction of movement of the current and when moving under the impulse of the current, will be rigid to secure the necessary propulsion.

15 A further object of the invention is to provide a device of this character which may be very readily and cheaply constructed and installed, which will be durable and efficient in service and a general improvement in the 20 art.

These and other objects I attain by the construction shown in the accompanying drawing, wherein for the purpose of illustration is shown a preferred embodiment of 25 my invention and wherein:

Figure 1 is a side elevation of a current motor constructed in accordance with my invention;

Figure 2 is a plan view thereof;

30 Figure 3 is a detail side elevation of a portion of the chain illustrating the manner of constructing the blades and connecting them to the chain.

Referring now more particularly to the 35 drawings, the numeral 10 generally designates a horizontally directed rigid frame, preferably in the form of an open rectangle having adjacent opposite ends of the opening opposed pairs of bearings 11, in which 40 are rotatably mounted shafts 12. Mounted upon each shaft adjacent each bearing is a sprocket 13 and chains 14 are trained about aligned sprockets of the shafts. Spaced links of the chain, preferably alternate links, 45 are provided with ears 15 and aligned ears 15 of the chains are connected by pivot rods 16.

Upon each pivot rod 16 is pivoted the inner end of a blade, generally designated at 50 17. Each blade comprises a plurality of sections 18, of which the innermost section 18 is secured to the pivot rod. Adjacent sections 18 are connected by applying to the rear faces thereof at abutting edges of the 55 sections L-shaped plates, one arm 19 of which is secured to the section and the other

arm 20 of which is formed with a pivot eye 21. The pivot eyes of the arms 20 at adjacent edges of the sections combine to receive transversely extending pivot rods 22 and the 60 innermost rod 22 of each blade 17 is connected by a chain or other flexible element, indicated at 23, with the pivot rod 16 of the following blade 17.

It will be obvious that with a construction 65 of this character, the blade 17 may readily fold to permit them to lie flatly against the chains during upstream travel and to permit them to conform to the surface of the sprockets 13 during their passage thereabout. At 70 the same time, when the sections are moved into aligned engagement, they are rigidified to one another by engagement of the end sections with one another and by the flat engagement of the confronting arms 20 of the 75 L-shaped plates.

It will be obvious that a device of this 80 character may be very conveniently located in any running stream and will operate without regard to the depth of the water at different times, provided the under runs of the 85 chains 14 are always so positioned that the blades 17 carried thereby are extended into the current. If desired, a housing 24 may be provided to cover the sprockets and the upper runs of the chain to protect the same against damaging contact with floating debris.

Since the construction hereinbefore set 90 forth is capable of a certain range of change and modification without materially departing from the spirit of the invention, I do not limit myself to such specific structure except as hereinafter claimed.

I claim:

1. In a current motor and a housing, a frame, supports affixed to the frame, sprockets having shafts journaled in the supports, endless chains passing over the sprockets, feathering blades pivoted to the chains in 100 spaced relation to each other, said blades being composed of two sections hinged together so that they may drop down into the current to propel the chains, and feather upon the chains on their return against the 105 current, the hinge being so formed that the parts, when extended, abut edge to edge and are held rigidly in this position by the hinge, flexible connections for each blade further supporting the blades in a perpendicular position with relation to the rotating chain, 110 said flexible connections being attached at 115

one end to the hinge of the upper-most blade section, and extending in a direction reverse to the direction of movement of the chain, and being attached to the pivot of the next succeeding blade.

2. In a current motor, an endless flexible element, feathering blades pivoted to the element, said blades being composed of two sections hinged together so that they may drop down into the current to propel the element and feather on the element on their return

against the current, the hinge being formed of two L-shaped plates, a pintle coating therewith and the two plates abutting against each other when the blades abut and prevent further swinging movement of the blades, the hinges being disposed on the upstream side of the blades.

15 In testimony whereof I hereunto affix my signature.

JESSE R. MEEKINS.
